ALL-PURPOSE UTILITY PENCIL CASE

Verona Pearl Amoth, Crosby, N. Dak.

Application October 12, 1944, Serial No. 558,409

3 Claims. (Cl. 211—69)

1

The invention relates to a utility case, and more especially to an all-purpose pencil carrier or holder.

The primary object of the invention is the provision of a device of this character, wherein a number of pencils can be conveniently carried, ready for service and selection, either on the person or upon a support, such as a desk or the like, the device when worn on the person prevents the wearing of holes in the pockets, the points of the pencils being protected and prevented from puncturing a garment during the carrying thereof.

Another object of the invention is the provision of a device of this character, wherein each pencil or other writing instrument is separately confined, and is readily accessible for handy use, the device being novel and unique, and the pencils when held thereby are secure and in order.

A further object of the invention is the provision of a device of this character, wherein the holding of the pencils eliminates breaking thereof when carried in their orderly manner.

A still further object of the invention is the provision of a device of this character, which is simple in construction, thoroughly reliable and efficient in purpose, strong, durable, neat in appearance, enabling a pencil to be selected with dispatch, and inexpensive to manufacture.

With these and other objects in view, the invention consists in the features of construction, combination and arrangement of parts as will be hereinafter set forth in detail, illustrated in the accompanying drawings, which show the preferred and modified forms of construction thereof, and pointed out in the claims hereunto appended.

In the accompanying drawings—

Figure 1 is a front elevation of the device constructed in accordance with the invention.

Figure 2 is a side view.

Figure 3 is a sectional view taken on the line 3—3 of Figure 1 looking in the direction of the arrows.

Figure 4 is a view similar to Figure 3 showing the swinging prop partly extended.

Figure 5 is a fragmentary perspective view of the prop, detached.

Figure 6 is a sectional view taken on the line 6—6 of Figure 3 looking in the direction of the arrows.

Figure 7 is a rear elevation of the device.

Figure 8 is a sectional view taken on the line 8—8 of Figure 7 looking in the direction of the arrows.

2

Figure 9 is a side view showing the device in standing position on a support.

Similar reference characters indicate corresponding parts throughout the several views in the drawings.

Referring to the drawings in detail, A designates generally the device constructed in accordance with the invention in its entirety, and in this instance, comprises a flat faced substantially rectangular shaped casing 10, having the rounded corners 11 and edges 12, respectively, while the front face 13 is solid, and the back face 14 is windowed, the latter being normally closed by a shutter-like prop 15. The prop 15 is provided with flexible pivot arms 16 formed with socketed trunnions 17, there being removably fitted in seats 18 therefor formed in the inner faces of the side edges 19 of the casing 10, so that the said prop can be swung to a position for 20 propping the casing on a support in a forwardly direction, as best seen in Figure 9 of the drawings, and in this manner, the device serves as a stand for pencils on a desk or the like. The prop 15 when closed is fractionally latched as at 20, best seen in Figure 3 of the drawings.

Formed interiorly of the casing 10 at its bottom portion are horizontally spaced pencil point pockets or seats 21, which are tapered correspondingly to the points of pencils 22 to be received thereby.

In vertical alignment with these pockets or seats 21 and formed in the top edge of the casing 10 are pencil receiving holes or clearances 23, so that the pencils 22 can be removably inserted 35 into the casing 10 to direct the points into the seats or pockets 21, with the blunt or rubber carrying ends of the said pencils protruding outwardly of the casing for a limited degree, whereby they may be selectively acquired for service.

40 The casing can be made of any selected material and may be of any desired size, while the pencil grouping can be varied. This casing 10 can be worn in the pocket of a garment or brought to a standing position on a support, 45 which is optional with a user thereof. The casing 10 also can be hung on a nail or the like, a hole 24 being provided for this purpose.

Supplemental seats 25 are provided for the arms 16, which are brought into use when the 50 device is placed in a standing position on a support, as shown in Figure 9 of the drawings, the trunnions 17 being interchangeable in such seats 18 and 25, as should be obvious.

What is claimed is:

55 1. A device of the kind described, comprising a

casing having a solid front and a window in the back, a plurality of pencil point seats interiorly thereof near one end and engageable through openings in the opposite end of the casing, and a prop carried by the casing at the rear side thereof adapted to close said window when in inoperative position and support said casing when in operative position.

2. A device of the kind described, comprising a casing having a solid front and a window in the back, a plurality of pencil point seats interiorly thereof near one end and engageable through openings in the opposite end of the casing, a prop carried by the casing at the rear side thereof and means swingingly connecting the prop for moving the prop into and out of

engagement with the window in the back of the casing.

3. A device of the kind described, comprising a casing having a solid front and a window in the back, a plurality of pencil point seats interiorly thereof near one end and engageable through openings in the opposite end of the casing, a prop carried by the casing at the rear side thereof, means swingingly connecting the prop for moving the prop into active and inactive relation with the casing and means for frictionally latching the prop in an inactive position and in fitting relation to the window in the rear of the casing.
